UNITED STATES PATENT OFFICE.

HUGH McDougall, of BROOKLYN, NEW YORK.

BUTTON AND STUD.

SPECIFICATION forming part of Letters Patent No. 235,446, dated December 14, 1880.

Application filed October 28, 1880. (No model.)

To all whom it may concern:

Be it known that I, HUGH McDougall, of Brooklyn, in the county of Kings and State of New York, have invented certain new and useful Improvements in Buttons and Studs, of which the following is a specification.

My invention relates to sleeve-buttons, collar-buttons, and studs, in which are combined a front plate, a post projecting therefrom, and provided with a fixed arm, a movable arm secured to the post by a pivot arranged parallel with said front plate, and a catch for holding said movable arm in a locked position when desired.

The invention consists in the combination of a front plate, a post projecting therefrom, and provided with a fixed arm, a movable arm secured to the post by a pivot arranged parallel with said front plate, and provided with a projecting toe, a spindle capable of being turned, and extending beyond the edge of said front plate, and a catch upon said spindle for engaging with the toe upon the movable arm, and adapted to be disengaged therefrom by the turning of the spindle. The said spindle is preferably provided in rear of said shoulder or catch with a stop to prevent the undue movement of the movable arm, and I may also combine with the said spindle and its catch a spring for turning said spindle and causing said catch to automatically engage with the toe upon said movable arm.

In the accompanying drawings, Figure 1 represents a perspective view of the under side of a sleeve-button embodying my invention. Fig. 2 represents a transverse section thereof. Fig. 3 represents a transverse section thereof upon the dotted line $\alpha\alpha$, Fig. 1; and Fig. 4 represents a horizontal section through the post and the toe of the movable arm and a view of the under side of the front plate and appurtenances, all the figures being made on an enlarged scale for the sake of more clearly illustrating my invention.

A designates the front plate, which may be of any desired shape and material, preferably metal, and which may be decorated or finished in any suitable style to suit the taste of the manufacturer. Upon the under side of said front plate is rigidly secured a post, B, the lower portion of which is bent over trans-

versely to the post proper, so as to form a fixed arm, C. The post and arm are represented as composed of a single strip or bar bent so as to form a bow-shaped arm and an open post, the two ends being fixed to the front plate, A; but said post and arm might be otherwise formed.

D designates a movable arm, pivoted in open post B by a pivot or pin, a, arranged parallel with the front plate, A, and having extending transversely to it a toe or gate, b.

When the button is to be inserted in a button-hole the arm D is turned on its pivot or pin a so as to bring it into a position approximately parallel with the arm C, as shown clearly in dotted outline in Fig. 2.

Upon the back of the front plate, A, and projecting beyond the edge thereof, is a spindle, c, which is so arranged in a bearing, d, and in the rim of the front plate, A, that it may be conveniently turned or oscillated, and which is provided outside the rim or edge of the front piece with a thumb-piece, c', whereby it may be turned or oscillated. On its under side the spindle c has a slanting or cam-shaped incline, as seen in Fig. 2, which terminates in an abrupt shoulder or catch, e, and in rear of said catch is a long projection, f, upon the spindle, which serves as a stop to prevent undue movement of the movable arm D. The movable arm D is preferably somewhat shorter than the bow-shaped arm C, so that it may be swung back within the arm C when the button is to be inserted. After the arms C and D are inserted through the button-hole the arm D is turned toward a position approximately in line with the arm C, and the toe or gate b, bearing upon the inclined or slanted cam-shaped surface upon the spindle c, turns the latter until the said gate or toe passes the catch e and strikes against the stop f, whereby its undue movement past the position shown is prevented.

In order to cause the spindle c to spring back at once when the toe or gate passes the catch e, I preferably employ a spring, g, one end of which is fixed to the under side of the front plate, A, at g', and the other end of which passes under the stop f and over the spindle.

When it is desired to unlock the button to

remove it from the button-hole, all that is necessary is to move the thumb-piece *c'* to oscillate the spindle *c* and move the catch *c* out of engagement with the toe or gate *b*, whereupon the movable arm *D* may swing up into a position parallel with the fixed arm *C*.

What I claim as my invention, and desire to secure by Letters Patent, is—

1. The combination of a front plate, a post projecting therefrom and provided with a fixed arm, a movable arm secured to the post by a pivot arranged parallel with said front plate, and provided with a projecting toe, a spindle extending beyond the edge of the front plate, and capable of being turned, and a catch upon said spindle for engaging with said toe, and adapted by the turning of said spindle to be disengaged therefrom, substantially as specified.

2. The combination of a front plate, a post projecting therefrom and provided with a fixed arm, a movable arm secured to the post by a

pivot arranged parallel with said front plate, and provided with a projecting toe, a spindle extending beyond the edge of said front plate 25 and capable of being turned, a catch upon said spindle for engaging with said toe, and a stop upon said spindle in rear of said catch, substantially as specified.

3. The combination of a front plate, a post 30 projecting therefrom and provided with a fixed arm, a movable arm secured to said post by a pivot arranged parallel with said front plate and provided with a projecting toe, a spindle extending beyond the edge of the front plate 35 and capable of being turned, a catch upon said spindle for engaging with said toe, and adapted by turning said spindle to be disengaged therefrom, and a spring for returning said rod, substantially as specified.

HUGH McDougall.
